CABLE ANCHORAGE

Clement Kendall, Morristown, N. J.

Application May 10, 1933, Serial No. 670,362

4 Claims. (Cl. 14—21)

This invention relates to a novel method and apparatus for anchoring cables, and more particularly to that type of cable composed of a multiplicity of strands, and widely used in the construction of suspension bridges and the like.

One object of the present invention is to provide a novel method and apparatus for enabling the complete installation of a strand anchorage frame before the cable ends are tensioned and secured thereto.

Another object is the provision of a novel fabricated strand anchorage frame which is easily assembled after being connected to the conventional anchorage bars and before the cable ends are introduced into the frame.

A further object is to provide novel cable end sockets and bearing blocks to cooperate with the strand anchorage frame of the invention in such manner as to enable a most rapid and accurate anchorage for cables of the class described.

These and still further objects of the invention will be apparent after referring to the drawings, in which:

Figure 1 is an end elevation of the apparatus of the invention.

Figure 2 is an enlarged detail elevation.

Figure 3 is a fragmentary plan.

Figure 4 is a view on the line IV—IV of Figure 2.

Figure 5 is a sectional detail of the novel bearing blocks and cable end sockets of the invention.

Figure 6 is a perspective view of a shim used for spacing the cable end sockets from the bearing blocks.

Figure 7 is an enlarged detail elevation of a modification of the invention.

Figure 8 is a sectional view of the line VIII—VIII of Figure 7.

Figure 9 is a perspective view of a modified form of shim for maintaining the cables in tensioned position.

Referring more particularly to the drawings, the numeral 2 designates a foundation of cement or other anchorage material, to which it is desired to anchor the cables of suspension bridges and the like.

A number of channels 3, or other structural shapes, are embedded in the foundation 2 and connected to the eyelets 4^a of a plurality of anchorage bars 4 by means of rods 5. The other extremities of the anchorage bars 4 extend out of the foundation 2 and are provided with eyelets 4^b.

A plurality of channel members 6 are provided with smaller interfitting reenforcing channels 7

and the two secured together, as by riveting their webs, as at 8. Each unit, composed of the channels 6 and 7, is bored to enable connection with the eyelets 4^b of the anchorage bars 4, and disposed with its flanges facing the flanges of the next adjacent unit, properly spaced relative to each other and secured together at each corner of the assembly by means of continuous angle members 9, which are bolted along their respective lengths, as at 10.

The units composed of the channels 6 and 7 are also connected together by smaller angle members 12 which are secured to the flanges of the outside channels of adjacent face-to-face assemblies.

In practice, the distance between the facing edges of the flanges of channels 6 and 7 is slightly greater than the thickness of the eyelets 4^b of the anchorage bars, permitting them to be secured to the units by means of pins 14 which extend throughout their length and are held in position by means of nuts 15 which are threaded on their ends.

The cables to be anchored, indicated at 16, are each provided with a T-shaped bearing block 17, of such dimensions as to pass through the spaces between the webs of the outside channels 6 of adjacent face-to-face unit assemblies when its longest surface is vertically disposed. A socket 18 is provided for each of the cable ends and is cut out as at 19 to enable the usual "brooming" and "soldering". The sockets 18 are of dimensions similar to those of the bearing blocks 17 in that they too are capable of passing between the webs of adjacent channels 6 when their longest surfaces are vertically disposed.

Suitable shims 20 are provided for spacing the sockets 18 from the bearing blocks 17 in order to tension the cables 16.

In installing the device of the invention, the two top angles 9 are unbolted and removed. This permits the introduction of the anchorage bar eyelets 4^b between the face-to-face units of the channels 6 and 7 of the anchorage frame. The lowermost of the anchorage bar pins 14 is then inserted through the apertures in the units 6 and 7 and the eyelets 4^b.

The operation is continued until the remaining eyelets 4^b are installed. The two bottom angles 9 are then unbolted, after which the whole anchorage frame is drawn taut by tightening the nuts 15, or other means. The bolt holes in the angles 9 are preferably reamed and the structure permanently secured as by bolting, shown at 10, it being understood that the use

of larger bolts will be necessary after the reaming than those formerly used.

The cables 16 are tensioned, and the sockets 18 on their ends, together with the bearing blocks 17, are drawn through the openings between the webs 6 of the channel units and turned at right angles to prevent their movement out of the strand anchorage frame.

A sufficient number of shims 20 are inserted 10 between the sockets 18 and bearing blocks 17 and the tension on the cables 16 released, permitting both socket and bearing block to rest on the adjacent small angle member 12.

Referring to Figures 7, 8 and 9, a modified 15 form of the invention is disclosed as embodying a combined cable end socket and bearing block 21. In practicing this form of the invention, the combined socket and bearing blocks 21 are cut out, as at 22, to enable "brooming" and 20 "soldering", and an extension 21^a provided for disposal between adjacent back-to-back channel members 6. The combined cable end socket and bearing blocks are spaced from the anchorage frame, in order to tension the cables 25 16, by means of a modified form of shim 23.

While I have shown and described several specific embodiments of my invention, it will be understood that I do not wish to be limited exactly thereto, since various modifications may 30 be made without departing from the scope of my invention, as defined in the following claims.

I claim:

1. A cable anchorage comprising, in combination, an anchorage frame, said anchorage frame 35 being composed of a plurality of channels arranged in pairs with their respective web portions in adjacent relationship, a smaller channel disposed within and secured to each of said first named channels, a plurality of anchor bars having their ends disposed between the ends of the 40 respective flange portions of adjacent pairs of said first named channels, said anchor bars being connected to said anchorage frame, a plurality of cables disposed between the adjacent 45 web portions of each pair of said first named channels, a bearing block placed on each of said cables, a socket secured to the end of each of said cables, and a plurality of elongated angle members for maintaining said first named channels in spaced relationship with respect to each other, said sockets and bearing blocks being adapted to pass between the web portions of adjacent pairs of said first named channel members when disposed in a determined position and 50 to be locked against returning therethrough by being partially rotated on their axes.

2. A cable anchorage comprising, in combination, an anchorage frame, said anchorage frame being composed of a plurality of channels arranged in pairs with their respective web portions in adjacent relationship, a smaller channel disposed within and secured to each of said first named channels, a plurality of anchor bars having their ends disposed between the ends of the 55 respective flange portions of adjacent pairs of said first named channels, said anchor bars being connected to said anchorage frame, a plu-

rality of cables disposed between the adjacent web portions of each pair of said first named channels, a bearing block placed on each of said cables, a socket secured to the end of each of said cables, a plurality of elongated angle members for maintaining said first named channels in spaced relationship with respect to each other, said sockets and bearing blocks being adapted to pass between the web portions of adjacent pairs of said first named channel members when disposed in a determined position and to be locked against returning therethrough by being partially rotated on their axes, and a plurality of small angle members disposed between and secured to each pair of said first named channels, whereby each of said small angle members provides a seat for the socket and bearing block on one of said cables. 5

3. A cable anchorage comprising, in combination, an anchorage frame, said anchorage frame being composed of a plurality of channels arranged in pairs with their respective web portions in adjacent relationship, a plurality of anchor bars having their ends disposed between the ends of the respective flange portions of adjacent pairs of said channels, said anchor bars being connected to said anchorage frame, a plurality of cables disposed between the adjacent web portions of each pair of said channels, a bearing block placed on each of said cables, a socket secured to the end of each of said cables, and a plurality of elongated angle members for maintaining said channels in spaced relationship with respect to each other, said sockets and bearing blocks being adapted to pass between the web portions of adjacent pairs of said channel members when disposed in a determined position and to be locked against returning therethrough by being partially rotated on their axes. 20

4. A cable anchorage comprising, in combination, an anchorage frame, said anchorage frame being composed of a plurality of channels arranged in pairs with their respective web portions in adjacent relationship, a plurality of anchor bars having their ends disposed between the ends of the respective flange portions of adjacent pairs of said channels, said anchor bars being connected to said anchorage frame, a plurality of cables disposed between the adjacent web portions of each pair of said channels, a bearing block placed on each of said cables, a socket secured to the end of each of said cables, and a plurality of elongated angle members for maintaining said channels in spaced relationship with respect to each other, said sockets and bearing blocks being adapted to pass between the web portions of adjacent pairs of said channel members when disposed in a determined position and to be locked against returning therethrough by being partially rotated on their axes. 40

5. A cable anchorage comprising, in combination, an anchorage frame, said anchorage frame being composed of a plurality of channels arranged in pairs with their respective web portions in adjacent relationship, a plurality of anchor bars having their ends disposed between the ends of the respective flange portions of adjacent pairs of said channels, said anchor bars being connected to said anchorage frame, a plurality of cables disposed between the adjacent web portions of each pair of said channels, a bearing block placed on each of said cables, a socket secured to the end of each of said cables, and a plurality of elongated angle members for maintaining said channels in spaced relationship with respect to each other, said sockets and bearing blocks being adapted to pass between the web portions of adjacent pairs of said channel members when disposed in a determined position and to be locked against returning therethrough by being partially rotated on their axes and a plurality of small angle members disposed between and secured to each pair of said channels, whereby each of said small angle members provides a seat for the socket and bearing block on one of said cables. 45
